CARTRIDGE BELT FOR AUTOMATIC FIRE-
ARMS

Henry Alexander Faulkner, Shirley, and Roger David Wackrow, Birmingham, England, assignors to The Birmingham Small Arms Company Limited, Birmingham, England, a British company

Application May 13, 1939, Serial No. 273,570
In Great Britain May 20, 1938

5 Claims. (Cl. 89—35)

This invention relates to cartridge belts for automatic firearms, of the kind in which the belt is adapted to carry the cartridges laterally into the feed box of the firearm by any suitable form of intermittent feed mechanism, and permit of the cartridges being moved in an axial direction into the breech chamber of the reciprocating breech block.

The invention refers more particularly to cartridge belts of the kind comprising clips produced from sheet metal blanks, bent and shaped to form a partly cylindrical body part on opposite sides of which are formed joint lugs to receive joint pins whereby the links are articulated to form a continuous cartridge belt, the said body part being arranged to partly embrace the rear end of the cartridge which is held in the desired assembled position by ribs formed in the body part of the clip and arranged to engage with the rim of a cartridge of the rim type, or a single rib arranged to engage with the annular groove formed at the rear end of a rimless cartridge.

It has been previously proposed to provide a clip of the aforesaid kind produced from a sheet metal blank having a strip or extension on one side thereof, the said blank being adapted to be bent and shaped to form the body part of the clip with a pair of joint lugs on one side thereof, while the strip part or extension is adapted to be bent to form a joint lug on the opposite side of the clip, and also to be bent over the body part of the clip to form an outer strengthening member or reinforcement of same.

The object of the invention is to provide a construction and arrangement of cartridge belt clip of the aforesaid kind wherein the hinged clips, or one or more clips located between sections of a length of cartridge belt of the aforesaid kind, are adapted to disintegrate when a cartridge is removed therefrom.

According to this invention we provide an improved construction of cartridge belt clip of the aforesaid kind wherein the sections or members are produced from sheet metal blanks, bent and shaped to form a partly cylindrical body part on opposite sides of which are formed joint lugs to receive joint pins whereby the links are articulated, characterised in that the clip is formed in two parts which are held assembled by the insertion of a cartridge, and disintegrated when the cartridge is withdrawn, comprising an outer clip member having an inner part of circular formation arranged to embrace about one third of the circumference of the cartridge, and an outer

part which forms a joint lug and also embraces the said inner part and is further arranged to surround about two thirds of the circumference of the cartridge, and an inner clip member adapted to lie within the aforesaid outer clip member and surround about one third of the circumference of the cartridge, said inner clip member having formed thereon a pair of spaced joint lugs, and wherein the aforesaid outer and inner clip members are connected in pairs by means of a joint pin engaging with the joint lugs thereon.

Having set forth the characteristic features of our invention, we will now proceed to describe the said invention with reference to the accompanying drawing, in which:

Figures 1 and 1^a are respectively a side elevation and a plan view of a suitably shaped blank from which the outer part of a cartridge belt clip, constructed in accordance with this invention, is adapted to be produced.

Figures 2 and 2^a are respectively a side elevation and a plan view of a suitably shaped metal blank from which the inner part of the cartridge belt clip is adapted to be produced.

Figures 3, 3^a and 3^b are respectively an end elevation, a side elevation and a plan view of the outer part of the clip.

Figures 4, 4^a and 4^b are respectively a side elevation, an end elevation and a plan view of the inner part of the clip.

Figure 5 is an end elevation of a short length of cartridge belt, showing the two-part clips assembled and connected by cartridges, and Figure 5^a represents in dotted lines one unit detached or disintegrated.

Figures 6 and 7 show respectively a plan view and a side elevation of the cartridge belt.

According to one convenient mode of carrying the invention into practical effect, we provide a cartridge belt clip which is formed in two parts comprising an outer clip member of partly cylindrical formation adapted to surround about two thirds of the circumference of the cartridge, and an inner clip member arranged to lie within the outer clip member and adapted to surround about one third of the circumference of the cartridge. The outer clip member is produced from a sheet metal blank, such as shown in Figures 1 and 1^a, which is adapted to be bent and shaped to form the said outer clip member, as seen in Figures 3, 3^a and 3^b, in which the part 1 of said blank is bent into a part circular formation which constitutes the inner part 2 of the said outer clip member and is arranged to embrace

about one third of the circumference of the cartridge, the narrow extension 3 on one side of the said blank being bent backward and arranged to form the joint lug 4, while the wider extension 5 and a further narrower strip or extension 6 of the said blank are adapted to be bent over the inner part 2 and arranged to surround about two thirds of the cartridge.

The inner clip member, as seen in Figures 4, 10 4^a and 4^b, is similarly produced from a sheet metal blank 7, such as shown in Figures 2 and 2^a, in which said blank is formed a transverse slot 8, and the metal at the opposite outer ends 9 of the said slot 8 is bent to form a pair of spaced joint 15 lugs 10, while the other part of said blank is bent into a partly cylindrical formation which is adapted, when assembled in the outer clip member, to lie within the outer partly cylindrical portion 5 thereof with its inner transverse edge 11 abutting 20 against the transverse edge 12 of the inner part 2 of the outer clip member, while the narrow strip part 6 of the said outer clip member is arranged to lie in the gap between the spaced joint lugs 10 formed on the inner clip member, thus providing 25 a longitudinal support for the inner clip member when assembled within the outer clip member. An inner and an outer clip member are hingewise connected together by a joint pin 13 mounted in the spaced joint lug 10 of the inner clip member 30 and passing through the interposed joint lug 4 of the outer clip member, and when an inner clip member has been assembled within an outer clip member in the manner as previously described, and a cartridge 14 is inserted, the said 35 two parts are securely connected together and form a belt or chain of cartridges, as seen in Figures 5 to 7, ready for use in an automatic firearm, but in such member that when a cartridge is removed, the parts disintegrate and readily fall 40 apart, as seen in dotted lines in Figure 5^a.

At or near the rear ends of the partly cylindrical formations of the two-part clip arranged to embrace the cartridge 14, are formed two internal ribs or projections 16 arranged to engage the rim 45 15 of the cartridge 14, as seen in Figure 7, to position same in the clip, or a single rib or projection may be provided for engagement with the usual groove in a rimless cartridge, when it is desired to adapt the clip for use with cartridges 50 of that type. The front ends 17 of the aforesaid cylindrical formation of the two-part clip may be bent and shaped to support the cartridge and position same, as seen in Figure 7, so that the 55 nose or bullet of the projectile is directed into the breech chamber of the gun.

On the front ends of the aforesaid cylindrical formations of the two-part clip are formed projections 18 and 19 arranged to engage with guides formed in the feed mechanism of the gun. Also, 60 the front ends of the said cylindrical formations are suitably shaped to constitute an abutment which is adapted in known manner to support the clips and prevent longitudinal movement of same when the cartridges are being moved axially 65 therefrom into the breech chamber of the gun.

If desired all of the clips comprising a complete cartridge belt may be of two-part formation as before described, adapted to disintegrate when the cartridges are removed therefrom, or if de-

sired, a disintegrating clip may be located between sections made up of single clips, of the non-disintegrating type.

It will be readily understood that cartridge clips in accordance with this invention may be modified in shape for use with various types or sizes of cartridges to suit different firearms, without departing from the scope of the invention.

Having thus described our invention, what we claim is:

1. A cartridge belt for automatic firearms, comprising a clip formed in two parts which are adapted to be held assembled by the insertion of a cartridge and disintegrated when the cartridge is withdrawn, composed of an outer clip member 15 having an inner part of partly cylindrical formation arranged to embrace about one third of the circumference of the cartridge, and an outer part which forms a joint lug and also embraces the aforesaid inner part and is further arranged 20 to surround about two thirds of the circumference of the cartridge, an inner clip member adapted to lie within the aforesaid outer clip member and surround about one third of the circumference 25 of the cartridge, said inner clip member having formed thereon a pair of spaced joint lugs, and joint pins for the belt engaging the joint lugs of the outer and inner clip members.

2. A cartridge belt for automatic firearms comprising a clip formed in two parts which are 30 adapted to be held assembled by the insertion of a cartridge, and disintegrated when the cartridge is withdrawn, composed of an outer clip member made from a single piece of sheet metal bent to form an inner part of partly cylindrical formation 35 which surrounds about one third of the circumference of the cartridge case, and an outer part which is arranged to form a joint lug and surround about two thirds of the cartridge case, an inner clip member made from a single piece of 40 sheet metal slotted and bent to form a pair of spaced joint lugs and a partly cylindrical formation adapted to lie within the aforesaid outer clip member with its inner transverse edge abutting against the transverse edge of the inner part of 45 the aforesaid outer clip member.

3. A cartridge belt for automatic firearms, as claimed in claim 2, including means for positioning the cartridge in the assembled two part clip comprising ribs or projections formed at or near 50 the rear ends of the partly cylindrical formations, said ribs or projections being adapted to engage with the rim of a cartridge, or a groove in a rimless cartridge.

4. A cartridge belt for automatic firearms, as 55 claimed in claim 2, including means for positioning the cartridge in the assembled two part clip comprising bent parts or depressions formed in the front ends of the partly cylindrical formations of said clip.

5. A cartridge belt for automatic firearms according to claim 2, including means for supporting and guiding the cartridge belt through the feed mechanism of the gun comprising projections formed in the front and the rear ends of 65 the partly cylindrical formations of the two part clip.

HENRY ALEXANDER FAULKNER.
